UNITED STATES PATENT OFFICE.

JOHN CARLSSON, OF PITTSBURGH, PENNSYLVANIA.

BUILDING BLOCK.

Application filed November 24, 1924. Serial No. 751,804.

The present invention relates to building blocks, and more particularly to hollow or cellular building blocks such as are usually formed from concrete, clay or other cementitious or ceramic material.

I provide a building block of this character of novel shape, whereby it is particularly adapted for the construction of walls, as it provides air spaces at the mortar joints, eliminates the necessity for special corner blocks, and requires little mortar for the perfect bonding of the blocks. Other advantages of this block are due to its light weight and the ease with which it can be handled.

In the accompanying drawings:—

Figure 1 is a perspective view of a block embodying my invention;

Figures 2 and 3 are sectional plan views of two different types of wall adapted to be constructed from blocks of the character shown in Figure 1;

Figure 4 is a perspective view of a slightly modified form of block embodying my invention, and

Figure 5 is a sectional plan view of a wall adapted to be constructed from blocks of the character shown in Figure 4.

Referring to Figure 1, the block therein shown is substantially T-shaped and provided with comparatively large air cells extending transversely therethrough. The head 2 of the block is provided with two air cells 3 separated by a transverse web 4 and the leg 5 of the block is provided with a single air cell 6 separated from the air cells 3 by a web 7. The outer walls of the block are relatively thin and substantially of the same thickness as the webs 4 and 7. The block is formed with a fillet 8 in the corner angle between each side face 9 of the leg and the adjacent lower face 10 of the head of the block. These fillets are preferably rectangular in cross section, and the two fillets are of the same depth and the same width.

The head of the block projects laterally from each side of the leg thereof a distance a substantially equal to the height b of the leg of the block. The advantages of this relationship will be apparent by reference to Figures 2 and 3, wherein it will be seen that the blocks at the corners of the walls make a

perfect fit, leaving just enough space 11 for mortar.

The thickness c of the head of the block is less than the height b of the leg thereof, and the depth d of the fillets is substantially equal to the difference between the thickness c of the head and the height b of the leg of the block. The advantages of this relationship between the thickness of the head of the block and the height of the leg thereof will also be apparent by reference to Figures 2 and 3, wherein it will be seen that the blocks are adapted to be laid so as to provide a wall of any suitable thickness, leaving air spaces 12 and 13 at the mortar joints.

The distance a that the head of the block projects laterally from each side of the leg thereof is greater than the thickness c of the head of the block by an amount substantially equal to the width e of the fillets 8. The advantages of this relationship will also be apparent by reference to Figures 2 and 3, wherein it will be seen that it permits the blocks to make a substantially perfect fit at the corners of the walls.

The modified form of block as shown in Figures 4 and 5 is similar to that shown in Figures 1, 2 and 3, but is of heavier construction and has more air cells. The head 2' of the block is provided with three air cells 3' separated by transverse webs 4' and the leg 5' of the block is provided with two air cells 6' separated from each other and from the air cells 3' by webs 7'. This block, instead of having a fillet in the corner angle between each side face 9' of the leg and the adjacent lower face 10' of the head, has each side face 9' of the leg cut away adjacent the adjacent lower face 10' of the head, thereby providing the channels 14.

As in the previously described construction, the head of the block projects laterally from each side of the leg thereof a distance a' substantially equal to the height b' of the leg of the block. The distance a' is also approximately equal to one-half the width f of the leg. Also the height b' of the leg is approximately equal to the thickness c' of the head.

The above relationships between the thickness and amount of lateral projection of the head and the height and width of the leg of the block and the advantages thereof

will be apparent by reference to Figure 5. It will be noted that in this modified construction, the channels 14 provide twice as many air spaces 12' and 13' at the mortar joints as the corresponding air spaces 12 and 13 in the constructions shown in Figures 2 and 3.

I consider the fillets 8 of the Figure 1 block and the channels 14 of the Figure 4 block an important feature of my invention, because these fillets and channels allow the blocks to be fitted together as illustrated in Figures 2, 3 and 5, leaving the air spaces 12 and 13 or 12' and 13' at the joints between the blocks and substantially reducing the area of contact between the blocks, thereby reducing the amount of mortar required for bonding the blocks together. The additional air spaces 12 and 13 or 12' and 13', in conjunction with the cells 3 and 6 or 3' and 6' of the blocks, insure a dry wall. Furthermore, these air spaces 12 and 13 or 12' and 13' break the mortar joints, and thereby substantially eliminate the danger 25 of moisture seeping through the wall.

While I have shown and described two preferred embodiments of my invention, it will be understood that the invention is not limited to the exact details of construction shown, as the invention may be otherwise embodied within the scope of the appended claims without departing from the spirit of the invention.

I claim:

1. A wall structure formed of a plurality of reversely arranged blocks of substantially T-shaped form and having a head portion and a leg portion, the end faces of the head portion and the side faces of the leg portion of each block being closely adjacent end faces or side faces of other blocks, the leg of each block being wider at one portion than another whereby cavities are provided in the wall structure between portions of the legs of the blocks and the adjacent surfaces of other blocks, the length of the leg portion of each block being substantially equal to the thickness of the head portion, whereby the inner faces of the head portions of the blocks may overlap and be in substantial contact with portions

of reversely arranged blocks throughout the greater part of their length, substantially as described.

2. A substantially T-shaped building block having a fillet substantially rectangular in cross section in the corner angle between each side face of the leg of the block and the adjacent lower face of the head of the block, said fillets being of the same depth, the head of the block being of less thickness than the height of the leg thereof and the depth of the fillets being substantially equal to the difference between the thickness of said head and the height of said leg, substantially as described.

3. A substantially T-shaped building block having a fillet substantially rectangular in cross section in the corner angle between each side face of the leg of the block and the adjacent lower face of the head of the block, said fillets being of the same width, the head of the block projecting laterally from each side of the leg thereof a distance greater than the thickness of said head and the width of said fillets being substantially equal to the difference between said distance and said thickness, substantially as described.

4. A wall structure formed of a plurality of reversely arranged horizontally disposed blocks of substantially T-shaped form, the said blocks having a head portion of substantially uniform width and a leg portion, the length of the leg being substantially equal to the thickness of the head, whereby the inner faces of the head of each side leg are adjacent and overlap faces of reversely arranged blocks, the said leg of each block being wider at one point in its length than another to provide for the formation of cavities in the inner part of the wall structure, the overall width of the leg at any point being greater than the length of the overhang of the head beyond the leg, whereby the several end faces of the blocks and side faces of the legs may be closely adjacent, and the legs of the blocks have a maximum strength, substantially as described.

In testimony whereof I have hereunto set my hand.

JOHN CARLSSON.
